CLAIM

The ornamental design for an electrical box placement gauge, as shown.

DESCRIPTION

FIG. 1 is a front elevational view of an electrical box placement gauge showing our new design, the rear elevational view being an identical image;

FIG. 2 is a top plan view;

FIG. 3 is a bottom plan view;

FIG. 4 is a right side elevational view, the left side elevational view being an identical image; and

FIG. 5 is a top, front, and right side perspective view thereof.

FIG. 1.

FIG. 2.

FIG. 3.

FIG. 4.
